Eliphilet S. Scribner.

Letter Patent

The schedules referred to in these Letters Patent and making part of the same containing a description in the words of the said Eliphilet S. Scribner himself of his improvement called the centrifugal Power Proj.

To all whom these presents shall come. Be it known that I Eliphilet S. Scribner of the town of Goshen in the County of Madison and State of New York have invented a new and useful improvement and principle of the lever kind called the centrifugal power proj and the following is a full and exact description of the construction and operation of said machine as invented by me. Four posts or standards for large work and three for small or weak, strongly attached (by means of gages and bolts or in any other way most convenient) to a bed piece of a chosen size and length at a distance from each other that will comport with the use for which the proj may be intended and so far apart in the width as to admit a power beam or saddle of a chosen dimension to play between them one end of the beam is suspended between two of the posts or admitted through one post by means of a mortise when three posts only are used, and this secured by a strong anchor bolt in such a manner as to admit the other end to play up and down at pleasure, between the other two posts is suspended a tumbler or shaft from which projects an arm of a length suitable to the space required to perform the work for which the proj may be intended, on the end of the arm, (or what I call the moving fulcrum) is a gear to receive the one end of an iron lever termed an elliptic lever, on account of its shape which must be such as to require no eccentric to admit the centre of its attachment to the moving fulcrum to turn under the tumbler or shaft which must engage with a bolt that passes through the power beam and head of the elliptic lever which is admitted through the beam by means of a gage to one end of the tumbler outside of one of the posts is strongly attached a lever by means of wings on the shaft or tumbler as a lever on the lever or in any way most convenient. This lever is called the moving lever on account of its performing the great task of

DRAWING

in the operation of the press and when it is raised up it turns with it the moving fulcrum which raises the end of the power beam to which the upper end of the elliptic lever is attached and when the acting lever is again brought down it increases its power in proportion as the moving fulcrum approaches the line of the turnable's center consequently the power increases on the beam as the turnable is made it becomes more and more condensed with nearly a uniform force applied to the acting lever until it approaches a position which shall bring the moving fulcrum under the line of the turnable's center or to a point which shall range the two attachment of the elliptic lever under the line of the turnable's center hence the power becomes infinite and the principle may with propriety be called a natural one for condensing any substance whatever, And I have intended this principle for the following purposes and have brought it into use for most of them viz for printing packing goods of every description required. Do cotton, flax, tobacco & hemp or any articles that may require to be packed; for extracting or expressing oils and juices of every description which may require pressure in any degree more or less. designed for the clothes for the paper maker, for the dairy man and laundry man, for smoothing any kind of article that requires pressure to do it. Likewise for stamping or sealing and pasting and cutting metals of every description. The implement or stampers required to perform the above mentioned purposes must be in a form that will comport with their use and may be placed over the power beam or saddle at a chosen distance from either ^{end} placed in a socket formed in the beam or in a piece of wood or metal attached thereto, where a long fellow is to be attached to the end of the stampers as in the case of the iron will press it most plough with a joint wood top. The acting lever may receive its motion by the hand, where the press is intended for light purposes, but for heavy work the lever will be so long as to require a staff, a pulley, a wheel cap, to which may be rigged in any way most convenient. In the above I have endeavored to give a concise description of the principle and the manner of applying it to the various purposes above mentioned & of fixing a quantity of force for the printing press which requires two dimensions only one each side of a bed sufficiently large to contain the size of the paper which is to

to receive the impression. The shaft or handle is suspended between the two standards under the head of the press with a projecting arm or fulcrum at each end of the frame which play on the outside of the standards and there receive, each an elliptic lever, the heads of which are attached to a saddle that passes through a groove or mortise in each standard after opening a slot or cut that hangs over the head of the press, the acting lever is attached to the shaft as before mentioned and may receive its motion by any method most convenient. It will be obvious to apply this principle to paper on this principle may claim a superiority over any other lever principle now known. The printing press requires by far the larger quantity of metal to construct the same power which is obtained by a fine circular motion of the moving fulcrum, as in case of presses for all other purposes above mentioned, consequently the acting lever will start from any angle with the same ease according to the density of the substance to be pressed, which will in all cases correspond with the space and power, consequently much time and labor is saved in these operations compared with presses operating on other principles. The drawing on fine paper is the form used for light purposes; the one on coarse paper for heavy work and will (I hope) give a satisfactory application of the manner of applying the principle to these various purposes herein mentioned. These constitutes on this principle will vary in their proportion as to height, length, strength &c according to the use for which they may be intended.
